UNITED STATES PATENT OFFICE

113,569

DESIGN FOR A DRESS

Abraham Magesis, New York, N. Y.

Application January 11, 1939, Serial No. 82,288

Term of patent 3½ years

To all whom it may concern:

Be it known that I, Abraham Magesis, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein

Figure 1 is a front view of a dress showing my new design.

Figure 2 is a rear view of the dress shown in Figure 1.

The characteristic feature of my design resides in the combination on the dress disclosed of the specific sleeves and girdle which are Shirred in the manner shown, in association with the specific yoke as shown.

I claim:

The ornamental design for a dress, substantially as shown and described.

ABRAHAM MAGESIS.
